UNITED STATES PATENT OFFICE.

HENRY D. GARDY, OF CHESTER, PENNSYLVANIA.

DESIGN FOR A MATCH-SAFE.

SPECIFICATION forming part of Design No. 33,780, dated December 18, 1900.

Application filed May 9, 1900. Serial No. 16,095. Term of patent 7 years.

To all whom it may concern:

Be it known that I, HENRY D. GARDY, a citizen of the United States, residing at Chester, in the county of Hamilton and State of Pennsylvania, have invented and produced a new and original Design for a Match-Safe; and I do declare the following to be a full, clear, and exact description of the invention, such as will enable others skilled in the art to which it applies to make and use the same, reference being had to the accompanying drawings, and to the figures of reference marked thereon, which form a part of this specification.

Figure 1 is a front elevation of a pocket-register and match-safe embodying my new design. Fig. 2 is a top plan of the same.

As shown in the drawings, my design is for a match-safe provided with a dial-plate and a circular panel.

1 is the register-dial; 2, the circular panel

or mirror, the same being beveled, as shown at 3.

4 is a countersink or depression in the face of the match-safe at the bottom near one side.

5 is a cover for the safe, in the top of which is the depression, elliptical in outline, across the bottom of which are transverse ribs 6.

7 is a bevel on one edge of the cover.

8 is a scroll on the face of the match-safe. Having described my invention, what I claim as new, and desire to secure by Letters Patent, is—

The design for a match-safe as herein shown and described.

In testimony whereof I affix my signature in presence of two witnesses.

HENRY D. GARDY.
